UNITED STATES PATENT OFFICE.

JOSEPH W. WILSON, OF WYANDOTTE, KANSAS.

MIDDLENS-PURIFIER.

SPECIFICATION forming part of Letters Patent No. 278,207, dated May 22, 1883.

Application filed September 1, 1882. (No model.)

To all whom it may concern:

Be it known that I, JOSEPH W. WILSON, of Wyandotte, Wyandotte county, Kansas, have invented a new and Improved Middlings-Purifier, of which the following is a full, clear, and exact description.

My invention relates to improvements in middlings-purifiers; and it consists in the peculiar construction and arrangement of parts, 10 as hereinafter fully described, and pointed out in the claims.

Reference is to be had to the accompanying drawings, forming part of this specification, in which similar letters of reference indicate 15 corresponding parts in both the figures.

Figure 1 is a longitudinal sectional elevation of my improved middlings-purifier. Fig. 2 is a perspective view of the feeding apparatus.

A represents the bolt or sieve, located in 20 chamber B below the suction-chamber C, said bolt being mounted on the rollers E of the reciprocating frame F, to which the power is applied from the shaft G by the connecting-rod H. The said reciprocating frame F is also 25 mounted on rollers E', said rollers being attached to the sides of the purifier-frame. My object in running the frame F on rollers instead of having it supported by springs is to enable me to have the middlings move from 30 the head end of the bolt to the lower or tail end of the bolt on a perfect plane, entirely free of rising and falling motion common to all bolts or sieves suspended by springs. It will be understood that by this sliding action I am 35 enabled to effect a much more perfect separation of the middlings and impurities than is possible by the rocking or rising-and-falling motion heretofore in use.

In order to regulate the air-currents produced in the bolt-chamber B by the fan I for carrying off the matters to be separated thereby, I arrange the series of chutes J and valves K between said chambers B and C, connecting the valves in several series of two or more 40 valves together by rods L with adjusting-levers M, said levers being outside of the chest, where they can be shifted readily at any time to regulate the openings and vary them along the chest as required in the different parts 45 for suiting the currents of air to the different localities of the machine. The levers M are attached to the pivot of one of the valves in

the respective series, said pivot being extended out through a hole in the chest, and they may have any approved ratchet contrivance, N, for securing them in the different positions. The fan draws the light matters separated by the air into it through the openings O, and expels them through spout P into any approved conductor, for delivery into the 55 dust-room or elsewhere.

For feeding the middlings to the bolt I have a shoe, consisting of bottom Q, sides R, back S, and feed-board T, attached to the head of the bolt, as shown in Fig. 1, onto which the 60 middlings are delivered from the stationary box V, attached to the frame of the bolt above said shoe, and into which the middlings are delivered at W from a spout. The feed-board T is made a little higher in the middle than at 65 the sides of the shoe, to insure the spreading of the middlings to the sides, and the box V is provided with notched lower edges, X, on the side next to said feed-board, to facilitate the feeding of the middlings in regular measure 70 from side to side of the bolt by breaking the lumps and acting as a kind of rake to distribute the matters evenly to the feed-board. These notched edges are also raised higher along the middle of the box than at the sides, 75 and they are also adjustably attached to the box by thumb-screws Y, or other approved means, so that they can be adjusted to regulate the volume of the middlings as desired. They are located a little back of the feed-board, 80 to cause the middlings to first pass under them and then flow along a short level before arriving at the place of falling over the feed-board. A ledge or chute, Z, at the back 85 of the box prevents the escape of the middlings thereat. Similar or other approved contrivance may be employed to prevent the escape of the middlings over the sides R of the shoe. It will be readily understood that by 90 this improved feeding-shoe a very uniform action will be secured, and it will also be seen that by the method now employed to regulate the action of the air the best results will be obtained from the fan-blast.

I am aware that a system of chutes and valves arranged between the bolt and suction-chambers has heretofore been employed. I am also aware that a sieve mounted on rollers is old, and I am further aware that a feeding-

shoe having a feed-board higher in the middle than at the sides is not broadly new, and I therefore do not claim such inventions.

Having thus described my invention, I claim
5 as new and desire to secure by Letters Patent—

1. The combination, with a feeding-shoe having a feed-board, T, made higher in the middle and descending each way to the sides of the shoe, of a box, V, having its edges X correspondingly higher in the middle and descending therefrom to the sides of the box, substantially as described.

2. The combination, with the feeding-shoe Q R S, having the feed-board T, made higher in the middle and descending to the sides, of the box V and the notched edges X, vertically adjustable on said box, substantially as and for the purpose set forth.

JOSEPH W. WILSON.
